Primary Examiner—Brian N. Vinson(74) *Attorney, Agent, or Firm*—Gifford, Krass, Groh, Sprinkle, Anderson & Citkowski, P.C.**CLAIM**

I claim the ornamental design for a merchandising display structure, as shown and described.

DESCRIPTION

FIG. 1 is a top, front, and left side perspective view of a merchandising display structure showing my new design; FIG. 2 is a front elevational view thereof; FIG. 3 is a top plan view thereof; FIG. 4 is a right side elevational view thereof; FIG. 5 is a rear elevational view thereof; FIG. 6 is a left side elevational view thereof; and, FIG. 7 is a bottom plan view thereof. The broken-line disclosure of wall mounting bracket is understood to be for illustrative purposes only and to form no part of the claimed design.
